UNITED STATES PATENT OFFICE.

WILLIAM FAIN AND ARTHUR REES, OF COALGOOD, KENTUCKY.

VALVE GRINDER.

Application filed January 24, 1923. Serial No. 614,606.

To all whom it may concern:

Be it known that we, WILLIAM FAIN and ARTHUR REES, citizens of the United States, residing at Coalgood, in the county of Harlan and State of Kentucky, have invented new and useful Improvements in Valve Grinders, of which the following is a specification.

This invention relates to tools for use in connection with repairing automobile engines and the like and has for its object the provision of a novel gear operated device adapted to be bolted onto an engine and operable to grind simultaneously all the valves, the device thus operating as a great time and labor saver.

Another object is the provision of a device of this character which may be used for grinding all the valves of an engine regardless of how many cylinders and valves there may be, the device being capable of attachment at different locations upon the cylinder block whereby to grind the valves in groups until the entire number has been treated.

A further object is the provision of a grinder of this character which includes supporting brackets detachably and adjustably mounted upon the cylinder block and pivotally carrying the valve grinding mechanism which is itself adjustable with respect to the supporting brackets.

Yet another object is the provision of a device of this character in which the valve engaging members and the centering devices therefor are adjustable longitudinally of their supports so that the device may be used to equal advantage regardless of whether the valves be close together or comparatively far apart.

An additional object is the provision of a device of this character which will be comparatively simple and inexpensive in manufacture, easy to operate, positive in action, efficient and durable in service and a general improvement in the art.

With the above and other objects and advantages in view the invention consists in the details of construction to be hereinafter more fully described and claimed and illustrated in the accompanying drawings, in which:

Figure 1 is a plan view of the device,

Figure 2 is a side elevation thereof mounted upon an engine,

Figure 3 is a cross section,

Figure 4 is a horizontal sectional view taken below the centering or upper plate,

Figure 5 is a plan view of the base member,

Figure 6 is a plan view of the centering plate,

Figure 7 is a detail sectional view through one of the operating gears and showing the mounting of the valve grinding member,

Figure 8 is a longitudinal section through one of the gear members and showing the valve grinding tool in fragmentary elevation and also illustrating the action of the tension regulating means,

Figure 9 is a detail sectional view showing the mounting of the rack bar,

Figure 10 is a detail plan view showing the upper and lower members of the slides detached,

Figure 11 is a detail edge elevation showing the manner of hingedly connecting the bracket members,

Figure 12 is a cross section on the line 12-12 of Figure 8,

Figure 13 is a cross section on the line 13-13 of Figure 8 and

Figure 14 is a detail cross section on the line 14-14 of Figure 8.

Referring more particularly to the drawings the letter A designates a cylinder block and B represents the valves to be ground. C represents the studs which project upwardly from the cylinder block and which are exposed when the cylinder head, not shown, is removed.

In carrying out our invention we provide a pair of bracket members designated broadly by the numeral 15, each of which includes an L-shaped member 16 designed to be placed upon the top of the cylinder block and formed with an elongated slot 17 for the accommodation of one of the studs C, it being understood that the usual nuts D are applied to these studs subsequently to the engagement of the bracket member 16 thereon. Each member 16 further includes an upstanding ear portion 18 having a serrated face 19. Each bracket 15 further includes a substantially L-shaped bracket member 20 terminating in an ear 21 having a serrated face 22 co-operating with the face 19, and the bracket members 16 and 20 are connected by a bolt 23 which passes through the ears 18 and 20 and which carries a clamping nut 24. The bracket members 20 are formed with bifurcations 25 for the reception of an

elongated preferably rectangular base plate 26 which is held within the bifurcations by means of wing screws 27 or the like. By this construction it will be seen that the base plate 26 may be positioned at any desired location in spaced relation above the cylinder block and that by loosening the nuts 24 the base plate may be swung so as not to be in obstructing relation to the cylinder block 10 so that access may be had to the valves or other mechanism.

The base plate 26 is formed with a longitudinal slot 28 which has its sides recessed as shown at 29. Slidably adjustably mounted upon this base plate are bearing members designated broadly by the numeral 30 and each of which includes a plate 31 lying within the recess 29 and formed with a reduced extension 32 fitting within the slot 28. 15 Each plate 31 is formed with an extension 33 through which passes a suitable set screw 34 for clamping the bearing members at adjusted positions along the slot and recesses. Disposed below the base plate 26 in engagement 20 with the underside thereof and associated with each bearing member 30 is a disk or other plate 35 secured to the reduced extension 32 by means of suitable screws 36. By this construction it will be seen that the 25 bearing members 30 may be slid to any desired position along the base plate while upward or downward displacement thereof is prevented and they may also be rigidly secured or clamped at such adjusted positions. 30 Journaled through each bearing member 30 is an elongated sleeve 37 having formed or secured thereon a spur pinion or gear 38 which is disposed above the base plate 26. The lower end of each sleeve is formed with 35 a reduced bore 38' angular in cross section for slidably holding the shank 39 of a valve engaging tool 40, the shank being held against displacement, while permitting longitudinal movement, by means of a spring 40 41 mounted upon the lower end of the sleeve and having an inwardly extending bent portion 42 constituting a catch and movable through a notch 43 in the sleeve so as to engage within a groove 44 in the shank. The 45 spring 41 has its free end extended outwardly in a curved direction as shown at 45 to facilitate its being grasped for the purpose of disengaging the bent catch portion 42 from the groove 44 so that the tool may 50 be removed when desired. At a point spaced below its upper end each shank 39 is formed or otherwise provided with a collar 46 against which abuts the lower end of a coil spring 47 located within the sleeve and 55 having its upper end engaged by a block 48 having a reduced extension 49 fitting within this spring. The purpose of this spring is to urge the valve engaging tool 40 downwardly and yet to permit it to yield upwardly. The 60 center of the upper surface of each block 65

48 is formed with a slight depression 50 for a purpose to be described and each block is held in position, within the sleeve by a split spring ring 51 engaged within a groove 52 in the inner wall of the sleeve. 70

Formed upon one end portion of the base plate 26 is a bracket member 53 carrying suitable bearings 54 for a shaft 55 having a crank handle 56 and carrying a disk or fly wheel 57. Slidable upon the base plate 26 75 is a rack bar 58 meshing with all the pinions 38 and prevented from lateral displacement by an upstanding flange 59 on the base plate. Upward displacement of the rack bar is prevented by lips 60 which overlie it 80 and which are formed on brackets 61 recessed into the flanged edge of the base plate and detachably secured thereon by suitable screws 62. The purpose of these brackets will be hereinafter explained. Carried by 85 the disk 57 is a wrist pin 63 with which is connected a pitman 64 connected with a pin 65 carried by the rack bar 58. By rotating the crank handle 56 it is apparent that the rack bar 58 will be reciprocated for turning 90 all the gears 38, and consequently the valve engaging tools simultaneously.

In addition to the brackets 61, we provide other brackets 66 which are secured upon the ends of the base plate 26 by means of 95 suitable screws 67 and these brackets 66 extend preferably to the same height as the brackets 61. It should be stated in passing that the brackets 61 are formed with inwardly extending lugs 68. 100

The numeral 69 designates the upper or centering plate which is spaced considerably above the base plate 26 and which has one edge resting upon the lugs 68. This centering plate is pivotally mounted with respect 105 to the brackets 66 by virtue of screws 70 which pass through the upper ends of the brackets 66 and which have unthreaded ends engaging within sockets 71 in the rear corners of the ends of the centering plate. The centering plate is held against casual pivotal movement by means of screws 72 which are threaded through the upper ends of the brackets 61 and into sockets 73 in the forward edge of the centering plate. 110

The centering plate is formed with a longitudinal slot 74 located above the slot 28 in the base plate and slidably mounted along this slot are bearing members designated broadly by the numeral 75. Each bearing member includes a plate 76 disposed upon the top of the centering plate and formed with a reduced extension 77 fitting within the slot 74. Each plate 76 is moreover provided with an extension 78 through 120 which passes a set screw 79 engaging the top of the centering plate for holding the bearing members in adjusted position in alignment with the bearing members 30. Each bearing member 75 also includes a 125

disk or other plate 80 secured against the lower end of the associated extension 77 by means of suitable screws or the like. The bearing members 75 are formed with threaded bores through which are screwed adjusting screws 81 which have tapered ends engaging within the depressions 50 in the blocks 48. By adjusting these screws it is apparent that the tension of the springs 47 which engage the valve grinding tools may be regulated so that the valves will bear with the desired pressure upon their seats.

In the operation of the device it will be seen that the brackets 15 are mounted upon the cylinder block in such a position that the valve grinding members 40 will be in proper position to align with the valves, the bearing members 30 are slid along the base plate 26 to bring these valve engaging tools properly in engagement with the valves and the set screws are tightened to maintain the adjustment. The centering plate is swung into position and held by the set screws 72, and the screws 81 are run up so that their ends may clear the upper ends of the sleeves 37. The bearing members 75 are then slid along the centering plate 69 until these screws 81 are in direct alignment with the sleeves 37, after which the screws 79 are tightened to maintain the adjustment. The screws 81 are then turned down until they engage the blocks 48 and the degree of turning depends upon the pressure desired to be exerted upon the valve engaging tools. After everything has been thus set, the operator grasps the handle 56 and turns the shaft 55 whereupon the action of the pitman 64 will result in reciprocation of the rack bar 58 and consequent rotation of the gears 38 and valve engaging tools. In this way the valves are alternately turned in opposite directions so that they may be ground properly to their seats it being of course understood that some suitable valve grinding compound must be applied to the valves or their seats.

The device is here illustrated as being built for use in grinding the valves of a four cylinder motor though it should be understood that it may be constructed longer for grinding the valves of engines having a greater number of cylinders, or if preferred, after the eight valves are ground the position of the device may be shifted so that the other eight may be ground or else two members may be left inactive at the first action so that only six valves will be ground, the remaining six being ground by a subsequent similar operation. However, these matters of arrangement, sizes and mode of operation are immaterial as the manufacturer may exercise his own judgment as to the sizes capable of most general use. These and other details of construction, materials, etc. are principally to be worked out

in actual practice and the right is reserved to make such and other changes provided that they do not depart from the spirit of the invention or the scope of the claims.

Having thus described our invention we claim:

1. A valve grinding machine comprising a supporting plate provided with attaching feet for connection upon the cylinder block of an engine, a plurality of sleeves journaled through said plate and carrying pinions, a longitudinally movable rack bar meshing with said pinions for effecting movement thereof, valve engaging tools detachably mounted within the lower ends of the sleeves, springs within said sleeves engaging said valve tools, and means for varying the tension on said springs, consisting of a top plate supported above said main plate, and screws threaded through the top plate and bearing upon buttons at the upper ends of the springs.

2. A valve grinding apparatus comprising supporting brackets adapted for adjustable connection upon a cylinder block, a base plate hingedly mounted upon said brackets, bearing members slidably adjustably mounted along the base plate, sleeves journaled through said bearing members and carrying gears, said sleeves being provided with chuck portions for holding valve grinding tools, a longitudinal movable rack bar meshing with all the gears and means for reciprocating the rack bar, and spring means within the sleeves normally urging the valve engaging tools into engagement with the valves of the engine.

3. A valve grinding apparatus comprising supporting brackets adapted for adjustable connection upon a cylinder block, a base plate hingedly mounted upon said brackets, bearing members slidably adjustably mounted along the base plate, sleeves journaled through said bearing members and carrying gears, said sleeves being provided with chuck portions for holding valve grinding tools, a longitudinal movable rack bar meshing with all the gears and means for reciprocating the rack bar, and spring means within the sleeves normally urging the valve engaging tools into engagement with the valves of the engine, and means for varying the tension on said springs.

4. A valve grinding apparatus comprising supporting brackets adapted for adjustable connection upon a cylinder block, a base plate hingedly mounted upon said brackets, bearing members slidably adjustably mounted along the base plate, sleeves journaled through said bearing members and carrying gears, said sleeves being provided with chuck portions for holding valve grinding tools, a longitudinal movable rack bar meshing with all the gears and means for reciprocating the rack bar, brackets

ing from said base plate, a centering plate carried by said last named brackets, a plurality of bearing members slidably adjustably mounted upon the centering plate and 5 formed with threaded bores, screws passing through said bores, springs within said sleeves urging the valve engaging tools downwardly, and blocks upon the upper ends of said springs engaged by said screws.

10 5. A valve grinding apparatus comprising slotted brackets adapted to be mounted adjustably upon the cylinder head retaining studs of an engine subsequent to the removal of the cylinder head, a main supporting plate carried by said brackets and 15 formed with a slot, bearing members adjustably mounted along said slot, sleeves journaled through said bearing members and carrying gears, valve engaging tools 20 detachably engaged within said sleeves, spring means within the sleeves urging said tools downwardly, and a longitudinally movable rack bar meshing with all of said gears.

6. A valve grinding apparatus comprising slotted brackets adapted to be mounted adjustably upon the cylinder head retaining studs of an engine subsequent to the removal of the cylinder head, a main supporting plate carried by said brackets and 30 formed with a slot, bearing members adjustably mounted along said slot, sleeves journaled through said bearing members and carrying gears, valve engaging tools 35 detachably engaged within said sleeves, spring means within the sleeves urging said tools downwardly, and a longitudinally movable rack bar meshing with all of said gears, and a centering plate adjustably mounted above said main plate and carrying 40 slidably adjustable bearing members carrying screws for varying the tension on said springs.

In testimony whereof we affix our signatures.

WILLIAM FAIN.
ARTHUR REES.
